UNITED STATES PATENT OFFICE.

CHARLES J. PERKINS, OF DES MOINES, IOWA.

COMBINATION MOVABLE SEAT AND SUPPORT.

1,241,434.

Specification of Letters Patent. Patented Sept. 25, 1917.

Application filed December 27, 1915. Serial No. 68,885.

To all whom it may concern:

Be it known that I, CHARLES J. PERKINS, a citizen of the United States, and resident of Des Moines, in the county of Polk and 5 State of Iowa, have invented a certain new and useful Combination Movable Seat and Support, of which the following is a specification.

The object of my invention is to provide 10 a combination movable seat and support of simple, durable and inexpensive construction.

A further object is to provide a device of 15 the class mentioned having a stationary supporting member, a seat member rotatably mounted thereon, and a suitable support operatively connected with said movable seat.

Still a further object is to provide such a 20 device so constructed and arranged that it may be readily and easily assembled or taken apart, and when so taken apart may be packed in a small space for storage or transportation.

My invention consists in the construction, 25 arrangement and combination of the various parts of the device whereby the objects contemplated are attained as hereinafter more fully set forth, pointed out in my claims and illustrated in the accompanying drawings, in which:

30 Figure 1 shows a side elevation of a milking stool embodying my invention.

Fig. 2 shows a top or plan view of the same.

35 Fig. 3 shows an inverted plan view of my milking stool, and

Fig. 4 shows a vertical, sectional view taken on the line 4—4 of Fig. 1.

In the accompanying drawings, I have 40 used the reference numeral 10 to indicate generally the seat member of the stool, which may be made of metal having at its periphery a downwardly turned flange 11.

Secured below the seat member 10 is a 45 turntable member 12 preferably in the form of a disk having near its periphery an upwardly extending bead 13, designed to engage the under surface of the seat 10 and hold the turntable member 12 spaced therefrom.

The turntable member 12 is pivotally 50 mounted on the seat 10 by means of a bolt 14, the head of which is mounted in a depression in the center of the member 10, and 55 the shank of which extends through the members 10 and 12.

Secured to the turntable member 12 are the upper ends of a substantially U-shaped supporting member 15, which is wider at its lower end than at its upper end. Secured 60 to the member 12 are arms 16 which extend downwardly and are pivoted at their lower ends to the arms of the member 15. Pivoted to the arms 16 are the upper ends of the arms of a U-shaped supporting member or 65 leg 17. In this connection attention may be called to the fact that the member 15 and the arms 16 are bolted or otherwise detachably secured to the member 12, so that they may be readily and easily detached, and the 70 parts of the supporting legs are so pivotally connected that when the members 15 and 16 are detached from the turntable member 12, the supporting legs may be folded together 75 in a small space.

Detachably secured to the member 10 are members 18 which converge toward each other at one point and then extend through a suitable slot in the downwardly extending flange 11 of the member 10, preferably in 80 parallel position away from the member 10.

At their outer ends the members 19 are bent away from each other to form a loop 20. The free ends of the members of the loop 20 are detachably secured together by 85 means of bolts 21 on which are wing nuts 12^a. Each member of the loop 20 is provided near its end with an opening to receive one of the bolts 21 and with an elongated slot 12^b adjacent to said opening to receive the other bolt 21. It will be seen that by loosening the wing nuts 12^a, the size of the loop 20 may be varied as desired for adjusting it for holding different sized implements or the like. 95

Detachably secured to the sides of the loop 20 are arms 23, which extend downwardly for a short distance and then are inclined inwardly toward each other at 24. The members 23 are extended downwardly a short 100 distance in order to clear the pail 22.

In the practical operation of my improved movable seat and support, the seat member thereon is placed in position and the leg member 17 adjusted to fit any inequalities 105 in the ground.

In Fig. 1 I have shown by dotted lines the leg 17 in one of its adjusted positions. The pail 22 is placed in the loop 20 and the roller 25 rests on the ground. If the cow becomes 110 restless or for any other reason the user of the stool desires to move the pail, it can be

swung horizontally and the roller 25 will travel easily, so that the pail holder may be easily moved to position where the contents of the pail will be out of the way.

5 In Fig. 2 the pail holder is shown in one position in full lines, and in another position in dotted lines.

10 It will be seen that the pail holder may be swung to position with its lower end adjacent to the lower end of the member 15. It may be noted that the members 15 and 16 are secured at their upper ends by means of bolts to the member 12, so that they can be readily removable, and at the same time, the members 23 are secured by means of detachable bolts, so that the device may be quickly and easily taken down for reducing the space which is occupied during storage or transportation.

15 20 It will be noted that the seat turns with relation to the turntable and the supporting legs, so that the seat and the pail holder member may be swung together, thus making it easy for the user of the stool to swing his body and the pail at the same time.

25 This feature of construction is believed to have considerable advantage in enabling the user to move the pail quickly and easily.

30 It will readily be seen that my improved device may be used for other purposes than as a milking stool.

35 35 The arms 19 which project away from the rotating seat and the members 20 and 24 may be readily modified for forming movable supports for other things besides pails, and it is not my intention to confine my invention for use as a milking stool only.

It will be understood that some changes

Copies of this patent may be obtained for five cents each, by addressing the "Commissioner of Patents, Washington, D. C."

may be made in the construction and arrangement of the parts of my improved 40 milking stool without departing from its essential features and purposes, and it is my intention to cover by this application any such changes which may be included within the scope of my claims.

45

I claim as my invention:

1. In a milking stool, a bail adapted to hold the pail, a seat member, means for rigidly supporting the bail and seat member spaced from each other and substantially 50 in horizontal alinement, a plate pivotally mounted beneath the seat member, a pair of spaced vertical legs extending downwardly from the plate, and a downwardly extending inclined leg having its upper end 55 pivotally mounted relative to the plate.

2. In a device of the class described, a bail, a seat member, means for supporting the seat member and bail in substantial horizontal alinement and spaced from each other, a plate below the seat member, a pivot pin extended through the center of the seat member and the plate, a pair of vertical legs extended downwardly from the plate from points on the opposite side of the pivot pin from the bail, a downwardly extending inclined leg having its upper end pivotally mounted relative to the plate whereby said last described leg may reciprocate in a vertical plane, which would pass through the centers of the seat member and the bail, and a supporting wheel secured to the bail with its axis substantially parallel with a radial line from the pivotal point.

70 Des Moines, Iowa, December 11, 1915.

CHARLES J. PERKINS.
